UNITED STATES PATENT OFFICE.

MARION MALLORY, OF TOLEDO, OHIO.

INDUCTION COIL FOR IGNITION SYSTEMS.

Application filed October 5, 1925. Serial No. 60,513.

My invention has for its object to provide an induction coil for ignition systems, particularly, of automobile engines that have parts that may be easily and cheaply constructed and assembled, whereby the coil may be made in quantities by unskilled labor and yet the coil will have the required efficiency that can ordinarily only be produced by careful machining and forming of parts and by exact placement thereof in assembling. The invention thus relates to a complete unitary structure comprising the core, the coil and a resistance element all of which coact each with the other parts of the coil. Also binding posts are provided and secured to the induction coil for readily establishing connections with external circuits and devices that form the automobile ignition system.

Constructions containing the invention may be varied in form or in their details. To illustrate a practical application of the invention I have selected an induction coil having core members that are so formed that they will secure and support the parts that form the unitary structure in definite positions relative to each other. The structure selected as an example is shown in the accompanying drawings.

Figure 1 of the drawings illustrates a side view of the induction coil, a part being shown broken away to illustrate a detail of the construction. Fig. 2 is a view of a vertical section taken on the plane of the line 2-2 indicated in Fig. 1. Fig. 3 is a top view of the induction coil. Fig. 4 is a broken view showing the means whereby parts of the induction coil are locked in position. Fig. 5 is a broken view showing a means for readily locating and securing the members that enclose the coil. Fig. 6 is a broken perspective view showing parts of the induction coil locked in position. Fig. 7 illustrates a perspective view of one of the caps that cooperate with the other parts of the induction coil to enclose the coil. Fig. 8 is a diagram of an ignition system in which the induction coil may be connected.

The particular induction coil selected for the purpose of setting forth a specific construction containing my invention is one that has a pair of air gaps in its magnetic circuit. Its magnetic circuit is completed through two parts that may be formed of magnetic material such as soft laminated iron. One of the parts forms a core that

may be termed an I-core and the other part a U-shaped magnetic member, the ends of the arms of the U-shaped magnetic member being located so that they extend over the ends of the core of the induction coil and so as to form an air gap in the magnetic circuit through the iron. Thus the I-core is located between the ends of the U-shaped magnetic members. If desired a second coil may be located on the U-shaped magnetic member between the arms to produce desired inductive effect in the induction coil. In the form of the construction shown the U-shaped member 1 forms the main supporting part or frame of the construction and also the means for maintaining the parts in their relation to each other. The U-shaped member has arms 2 that are substantially square in cross section and the coil 3, which comprises the primary coil 4, the secondary coil 5, and the laminated iron core 6, is secured between the ends of the arms 2 of the U-member 1 as best shown in Fig. 2.

In order that the coil may be protected from water and electrically insulated it is contained within a shell 7 which is closed by means of the caps 8 and 9. The shell and the caps are formed of insulating material. The caps 8 are provided with recesses 10 which fit the ends of the coil, preferably, so as to receive the ends of the primary coil 4 and thus sustain the coil in position within the shell 7. The recesses 10 are made of sufficient depth so as to place the ends of the I-core 6, which are also located in the recesses, in proximity to the ends of the arms 2 of the U-member 1 and thus form, magnetically speaking, a gap in the magnetic circuit between the I-core and the U-member 1. The spaces between the I-core and the U-member having substantially the same effect inductively as though the ends of the magnetic parts were separated by "air gaps." The caps 8 and 9 are also provided with channels 11 that are located in the peripheral portions of the caps as best shown in Fig. 7. The channels 11 have a depth and dimensions for receiving the end edge portions of the cylinder 7 and thus form a means for sealing the interior of the shell and preventing admission of moisture and dust within the shell. The coil 3 is thus maintained within a sealed enclosure which protects it from the atmosphere and from the dust of the road.

The wires from the coils 4 and 5 pro-

trude through the top and the bottom of the enclosure, that is, through the caps 8 and 9 and the secondary coil has a terminal that is connected to the distributor arm of the 5 ignition system. A binding post is located on the shell 7 for ready connection of the secondary coil 5 with the external circuit and in order to locate the binding post in position where connection may be readily 10 made, that is, in position where the binding post may be readily accessible and its parts readily operated, the caps 8 and 9 and the shell 7 have registering parts or members so that in the assembling the shell and the caps 15 may be readily located in a predetermined position relative to each other. In the construction shown the caps are each provided with portions 12 that protrude from the bottoms of the channels 11 or from cross ridges 20 within the narrow channels 11. The protruding portions 12, however, do not extend to the outer edges of the channels whereby the edges of the shell may be placed within the channels and guided thereby when rotated 25 relative to the caps. The edges of the shell are provided with notches 13 that fit around the protruding portions 12 so that when the edge portions of the shell are placed within the channels and rotated the 30 notches will quickly register with the raised portions and the edges of the cylinder will step into the bottoms of the channels. Each of the caps is provided with a hole 15. The primary coil 4 is of coarse wire and when 35 the caps are placed on the ends of the coil, the wires are inserted through the holes 15. In making up the coil 3 the end portions of the wire that form the primary coil are located on the same side of the coil. This is 40 also preferably true of the terminals of the secondary coil. The binding posts of the induction coil are located on one side of the shell 7 and at certain points on the caps 8 and 9. Thus by means of the registering 45 parts 12 and 13 and the holes 15, the parts of the induction coil may be definitely located with respect to each other with absolute certainty and yet with a readiness that greatly cheapens the cost of production and 50 all that is required is to make the bends in the wires to connect them with the binding posts.

One binding post is supported on the bracket 16 that is secured to the cap 9. The 55 end of the primary coil is bent over and secured to a binding post 17 that may be formed by means of the screw bolt 18 and the nuts 19. The bracket 16 may be secured by means of hollow rivets 20 that may be 60 cast or formed in the insulating material of which the cap 9 is formed. The other end of the primary coil may be bent about the binding post 21 that is secured in the cap 8. The end of the secondary coil may also be 65 passed through the opening 15 in the cap 8 and secured to the binding post 21 which joins the two coils together at this point. The other end of the secondary coil may be connected to the binding post 23 that is secured to the sleeve 7 preferably, at mid-point 70 and in the front of the induction coil for convenience of location. The connection is made, preferably, within the sleeve 7 and the distributor arm of the ignition system is connected to the binding post 23 by means of 75 the thumb nut 24 which may be formed of insulating material when the induction coil is to be installed.

When the caps have been placed in position on the cylinders the U-shaped magnetic 80 member 1 which fits the upper surfaces of the caps is forced into position so as to place the arms 2 across the outside surfaces of the caps and thus the parts are secured in position. In order to locate the sleeve and the 85 caps and the parts that they contain or which are supported thereby in a definite relation with respect to the U-shaped member 1 the caps are provided with recesses for receiving the arms 2. Preferably, parallel 90 ridges 27 are formed on the outer surfaces of the caps and are spaced apart so as to fit the sides of the arms 2 and thus the arms 2 may be slid between the ridges 27 to guide 95 them to a definite position or relation with respect to the caps and consequently with respect to the binding posts and the other parts of the induction coil. In order to limit the crosswise movement of the arms with respect to the caps and so as to definitely 100 locate them with respect to the ends of the I-core 6 of the coil, ridges 28 are located on the caps 8 and 9. The ridges 28 extend across and are spaced from the ends of the ridges 27. In order to locate the parts in 105 their relation, brackets 29 may be secured to the ends of the arms 2 by means of hollow rivets 25 and the bolt 26 and fit into recesses 110 or otherwise engage with the caps 8 and 9. In the form of construction shown a set of 115 ridges 30 extend parallel to the ridges 28 and to the ends of the ridges 27 and the brackets are so formed and have dimensions such that when they are secured to the ends of the arms 2 portions thereof will lie within 120 the space formed between the ridges and, preferably, press against the upper surfaces of the caps and thus will lock the parts in their relation to each other. The brackets are, preferably, angular in form and before assembly have portions that extend at an angle to each other that is greater than 90 degrees so that when they are secured to the ends of the arms 2 the portions that make 125 contact with the ends of the arms 2 will be drawn down and the brackets which may be formed of sheet metal having elasticity causes the caps to be elastically pressed against the ends of the shell and thus the container that is formed by the shell and 130

the caps and which encloses the coil will be elastically held in position as well as sealed. This prevents road shock and breakage and a well protected coil is produced by the means provided for the enclosure of the coil and the assembly of its parts.

In induction coils of the type described a resistance wire is sometimes used to increase the current quantity through the coil during 10 the starting operation or to maintain the current quantity substantially the same during that time. As is well known a starting motor requires a large current and the induction coil does not receive the current that 15 it receives when the automobile engine is running and consequently in order to give the ignition coil sufficient current when starting the resistance of the primary coil is made sufficiently low and to prevent the consumption of current during the operation of the engine a resistance is connected in series 20 with the primary coil. In starting the resistance is short circuited which allows a sufficient current to pass through the primary 25 coil to obtain effective ignition. In the assembly of the induction coil embodying my invention the resistance wire 31 is wound upon a horse shoe shaped insulating bar 32 preferably formed of mica and the 30 bar is readily supported in position by means of the binding post 21 and a second binding post 33 that is located on the opposite side of the arm 2 and on the cap 8 of the induction coil. The mica horse shoe shaped 35 bar 32 is placed over the ends of the binding posts 21 and 33 and is secured in position by suitable nuts 34.

A third coil 57 may be located upon the U-shaped magnetic member 1 and connected 40 in parallel with the primary coil 4 in order to produce the desired inductive effect on the secondary coil 5. The coil 51 is connected to the binding post 18 at one end and to the binding post 38 at the other end. The binding post 38 is insulatingly supported on the U-shaped magnetic member 1 which constitutes a core for the coil 51. The binding post 38 may be insulated by means of the washers 39 and an insulating sleeve 40. This 45 locates the binding post 38 in a convenient position for making connection with the binding post 21 to which one of the terminals of the primary coil 4 is connected. If desired a spring 42 may be secured to the binding post 38 so that when the U-shaped 50 magnetic member 1 is slid into position the spring 42 will make contact with the binding post 21. Preferably, the bolt that forms the binding post 38 will pass through a 55 sheet metal part 43 from which the spring contact 42 extends and the spring 42 will thus be held secured in position and at the same time connection will be established with the binding post.

60 Suitable mounting brackets 46 and 47 may be secured by the bolts 26 and 48 to the lower arm 2. The brackets 46 and 47 may be varied in shape according to the part of the car to which the induction coil is supported, in order to preferably support the 65 induction coil so that the core will be located in a vertical position.

The connections with the external circuit may be varied according to the ignition system in connection with which the induction 70 coil is used. In the diagram of Fig. 8 the resistance wire 31 is short circuited by means of the switch 50 and the connection is made to the terminals of the resistance wire and from the resistance wire 31 to the battery 59. 75 One end of each primary and secondary coil is connected to the end of the resistance wire and the remaining end of the primary coil is connected to the circuit breaker 52' while the remaining end of the secondary coil is 80 connected to the arm 53 of the distributor 85 54. The contacts of the distributor are connected to the spark plugs 55.

I claim:

1. In an induction coil, a U-shaped magnetic member, a shell, a coil located in the shell, a pair of caps for closing the ends of the shell, the caps having channels extending radially with respect to the center of the caps, the arms of the U-member fitting the 90 channels to secure the caps in position on the shell.

2. In an induction coil, a U-shaped magnetic member, a shell, a coil and its core located in the shell, a pair of caps for closing 100 the ends of the shell, the caps having channels extending radially with respect to the center of the caps, the arms of the U-member fitting the channels and extending over the 105 ends of the core and for securing the caps in position on the shell.

3. In an induction coil, a U-shaped magnetic member, a shell, a coil and its core located in the shell, the cross sectional areas of the magnetic member and the core substantially approximating each other, a pair of caps for closing the ends of the shell, the caps having channels extending radially with respect to the center of the caps, the arms of the U-member fitting the channels and 110 extending over the ends of the core and for securing the caps in position on the shell.

4. In an induction coil, a U-shaped magnetic member, a shell, a coil located in the shell, a pair of caps for closing the ends of the shell, the caps having recesses extending to the edges of the caps, the arms of the U-member fitting the recesses to secure the caps 120 in position on the shell.

5. In an induction coil, a U-shaped magnetic member, a shell, a coil located in the shell, a pair of caps for closing the ends of the shell, the caps having recesses and locking members secured at the ends of the arms 125 of the U-member and located in the recesses 130

for locking the caps in position relative to the shell.

6. In an induction coil, a U-shaped magnetic member, a shell, a coil located in the shell, a pair of caps for closing the ends of the shell, the caps having recesses extending to the edges of the caps, the arms of the U-shaped member fitting the recesses to secure the caps in position on the shell, the caps having a second set of recesses, locking members secured to the arms of the U-magnetic member and located in the second set of recesses for locking the caps in position on the shell and the arms to the caps.

7. In an induction coil, a shell, a coil lo-

cated in the shell, a pair of caps for closing the ends of the shell, a U-shaped magnetic member for securing the caps in position on the ends of the shell, the arms of the U-member fitting across the top surfaces of the caps, 20 binding posts located on the caps, a horse shoe shaped insulating member secured to two of the binding posts on opposite sides of one of the arms of the U-shaped member, a resistance wire located on the horse shoe 25 shaped insulating member.

In testimony whereof I have hereunto signed my name to this specification.

MARION MALLORY.
